UNITED STATES PATENT OFFICE.

ROBERT A. COOPER AND WILLIAM COOPER, OF EAST SMETHPORT, PENNSYLVANIA.

AUTOMATIC WOOD-GAS-REGULATING VALVE FOR DESTRUCTIVE-WOOD-DISTILLATION PLANTS.

1,269,392.

Specification of Letters Patent. Patented June 11, 1918.

Application filed June 10, 1916, Serial No. 102,867. Renewed January 12, 1918. Serial No. 211,671.

To all whom it may concern:

Be it known that we, ROBERT A. COOPER and WILLIAM COOPER, citizens of the United States, residing at East Smethport, in the 5 county of McKean and State of Pennsylvania, have invented certain new and useful Improvements in Automatic Wood-Gas-Regulating Valves for Destructive-Wood-Distillation Plants, of which the following is a 10 specification, reference being had therein to the accompanying drawing.

This invention relates to certain new and useful improvements in automatic wood gas regulating valves adapted to be used on one 15 or a battery of retorts in destructive wood distillation plants, for the purpose of controlling and equalizing the suction in the condensers so as to allow only the noncondensable gas or wood gas to be drawn from 20 the condensers to the boilers to be used as fuel.

Another object of our invention is to provide a valve which is adapted to be placed in the branch pipes connecting the condensers to the wood gas line pipe leading to the boiler so as to control the suction in 25 each condenser.

In wood distillation plants as now in use, suction is created in the condensers by steam 30 jets at the boilers, and in the present arrangement of wood distillation plants, the retorts nearest the boilers receive the heavier suction, and the retorts farthest removed the lightest suction.

With the ordinary slide valve placed in the wood gas line at each retort, the boiler jet is adjusted to draw away the gas from the retorts farthest from the boilers, and the 35 retorts nearest the boilers must necessarily be regulated by the hand slides to equalize the suction, and we have found by actual 40 experience and observation that a strong suction is created when the retorts run hot from accidental overfiring and results in drawing into the wood gas line from the condensers volatile gases, mostly methyl alcohol, which are thereby lost but which can be condensed by controlling the suction through the condenser, and the object of our invention is to 45 50 provide means for controlling the suction in the condensers in order to condense all of the condensable gases passing through the condensers.

In destructive wood distillation plants

employing a battery of retorts, the suction 55 created is greatest at the retort nearest the boiler, and less at the retort farthest removed therefrom, and the object of our invention is to provide an automatic regulating valve which is capable of being adjusted 60 so as to provide means for utilizing the same style of valve in each branch from the condensers as each valve is capable of being adjustable independently so as to regulate the suction in each condenser thereby preventing 65 the condensable gases from being drawn from the condensers.

Another object of our invention is to provide an automatic gas regulating valve for each condenser in the battery of condensers 70 and retorts in destructible wood distillation plants so constructed that each valve will operate automatically so as to control the suction from the boiler so as to prevent over- 75 suction.

Other and further objects and advantages of the invention will be hereinafter set forth and the novel features thereof defined by the appended claims.

In the drawings,

Figure 1 is a diagram of a destructive wood distillation plant showing the application of our improved construction of automatic wood gas regulating valve thereto.

Fig. 2 is a vertical section through our 85 improved construction of automatic wood gas regulating valve.

Fig. 3 is a longitudinal section through a portion of the outlet pipe of the condenser showing its connection with the gas line 90 pipe, the regulating valve being shown in elevation.

Like numerals of reference refer to like parts in the several figures of the drawing.

In the diagram shown in Fig. 1 we show 95 a series of retorts 1 connected to the condensers 2 by pipes 3 from which extend pipes 4 which are provided with the usual traps not shown, to prevent the noncondensable gases from passing off with the condensable gases. Each pipe 4 is provided with a vertical branch 5 in which is arranged a pipe section 6, the upper end of each branch terminating in a wood gas line 7, which extends to a boiler 8 having the usual steam pipe terminating in a steam jet within the wood gas line pipe 7 for creating suction therein, so as to draw the noncon-

80

100

105

densable gases from the condensers to the boiler to be used as fuel which is common in wood distillation plants as now constructed.

The construction of each automatic valve employed in the branch pipes connecting the outlet pipes 4 of the condenser to the wood gas line pipes 7 is identical, and the description of one will be sufficient for all. Extending from the pipe sections 6 is a casing 8' which is provided with a vertically disposed cylinder 9 in which is mounted a piston 10 having an adjustable piston rod 11 mounted therein which is provided with a threaded portion passing through the head 15 of the piston having a nut mounted upon each side of the head for adjusting the position of the piston rod therein. The opposite end of said piston rod is provided with a bifurcated portion in which is pivotally mounted the upper end of a pitman rod 12 which is pivotally mounted at its lower end on the double crank portion 13 of a damper rod 14, the ends of which are pivotally mounted in bearings 15 and 16 as clearly shown in Fig. 2. The end of the casing 8' is provided with a dial face 17 and the end of the damper rod 14 carries a pointer 18 over said dial face so as to indicate the position of the damper 19 carried by the damper rod 14 in the pipe section 6. The damper rod 14 is supported by a partition 20 in the casing 8' which terminates short of the upper end thereof leaving an opening in order to afford communication between the pipe section 6 and the casing 8' for the purpose hereinafter fully described.

The vertically disposed cylinder 9 is provided with an annular internal flange 21 forming a seat for a coil spring 22 arranged within the cylinder and upon the upper end of which is mounted the piston which is substantially inverted cup-shaped, and it will be seen that when the piston is drawn downwardly the spring will be compressed so that when the suction is reduced, the piston will be forced back into its normal position in order to hold the damper 19 in the pipe section 16 in vertical position therein, in order to allow a free passage of the non-condensable gases therethrough.

The upper end of the cylinder 9 is closed by a cap 23 which is provided with openings registering with openings 24 formed in the upper end of the cylinder so as to allow the air drawn into the cylinder on the downward movement of the piston to escape therefrom on the upward movement thereof.

It will be seen that by adjusting the nuts on the piston rod, the position of the piston in respect to the spring can be adjusted in order to regulate the action of the piston so as to cause the damper to open with less or greater suction which enables the valve to be adjusted to suit the branch pipe to which it is connected whereby the suction

in each branch pipe extending from the condensers will be regulated as the valve will open and close in proportion to the amount of suction so as to prevent the condensable gases from being drawn out of the condensers and carried to the boiler.

In the operation of our improved construction of automatic gas regulating valve applied to a destructive wood distillation plant as shown in the diagram in which three retorts are shown, each retort being connected to a condenser which are connected to the boiler by a wood gas line pipe having disposed between the wood gas line pipe and the outlet pipe of the condenser one of our improved construction of valve; the suction is created at the boiler by a steam jet, the suction at the first condenser will be greater than at the last condenser in the battery of condensers, and as the dampers are normally in open position to allow free passage of gas therethrough, the suction is created within the casing 8' and will draw the piston downwardly within the cylinder 9 so as to oscillate the damper 90 rod 14 so as to turn the damper 19 and partly close the section 6 so as to prevent oversuction within any of the branches of the condensers as in actual work suction will be exerted within the cylinder and through the medium of the piston will adjust the position of the damper in proportion to the suction which will prevent the condensable gases from being drawn out of the condensers.

While we have shown a particular construction of piston for controlling the position of the damper, it is, of course, understood that various other constructions could be used in connection with springs for returning the same to normal position without departing from the spirit of our invention, and we do not wish to limit ourselves to any particular construction of fluid controlled damper for regulating the suction in the condensers.

We claim.

1. In a wood distillation plant, the combination with a series of condensers, of a pipe connection from said condensers to the boiler of the plant, and a suction controlled damper for controlling the passage of gases through said pipe.

2. In a destructive wood distillation plant, the combination with a battery of condensers, of a boiler, a wood gas line pipe having a connection with said boiler, branch pipes connecting said condensers to said wood gas line pipe, dampers arranged in said branches, and fluid actuated means for controlling the position of said dampers.

3. In a destructive wood distillation plant, the combination with a battery of retorts and a battery of condensers connected together, of a boiler, a wood gas line

- 5 pipe extending from said boiler, means for
6 creating a suction in said pipe, a connection
7 between said pipe and condensers, and
8 a fluid controlled damper for controlling
9 the suction in each condenser.
- 10 4. In a destructive wood distillation
11 plant, the combination with a battery of
12 retorts and a battery of condensers, of a
13 boiler, a gas line pipe extending from said
14 boiler, means for creating a suction in said
15 pipe, a connection between each condenser,
16 and said pipe, and a fluid controlled damper
17 arranged within each of said connections.
- 18 5. A destructive wood distillation plant,
19 comprising a battery of retorts, a battery
20 of condensers, a boiler, and a connection
21 from said boiler to said condensers, means
22 for creating suction within said connection,
23 and fluid actuated means for controlling
24 the suction in each condenser.
- 25 6. A wood distillation plant having a con-
26 denser provided with an outlet having a
27 trap, a branch extending from said outlet,
28 a gas line pipe connected to said branch,
29 means for creating a suction in said gas line
30 pipe, a damper arranged within said branch,
31 and means for controlling the position of
32 said damper to regulate the suction in said
33 condenser.
- 34 7. A destructive wood distillation plant
35 having a condenser provided with an outlet
36 having a branch, a wood gas line pipe con-
37 nected to said branch, means for creating
38 suction within said wood gas line pipe, and
39 a fluid controlled damper arranged within
40 said branch.
- 41 8. In a wood distillation plant, the com-
42 bination with a condenser, of a wood gas
43 line pipe having a connection with said con-
44 denser, means for creating suction within
45 said wood gas line pipe, and a fluid con-
46 trolled damper for regulating the suction
47 within said condenser.
- 48 9. In a wood distillation plant, the com-
49 bination with a condenser having an outlet,
50 a branch connected to said outlet, a pipe
51 section arranged within said branch having
52 a casing provided with a cylinder, a damper
53 rod mounted within said casing extending
54 through said pipe section, a damper mounted
55 on said damper rod within said pipe section,
56 and a piston mounted within said cylinder
57 having a connection with said damper rod
58 for controlling the position of said damper
59 within said pipe section.
- 60 10. In a wood distillation plant, the com-
61 bination with an outlet pipe of a condenser,
62 of a pipe section connected thereto having a
63 damper controlling the passage of gas
64 therethrough, and suction actuated means
65 for adjusting the position of said damper.
- 66 11. In a wood distillation plant, the com-
67 bination with a condenser having an outlet
68 provided with a branch, of a pipe section
69 connected to said branch, a casing carried
70 by said pipe section, a cylinder carried by
71 said casing, a damper rod mounted within
72 said casing and pipe section, a damper car-
73 ried by said damper rod, said damper rod
74 having a double crank portion, and a spring
75 returned piston mounted within said cylinder
76 having a connection with said crank por-
77 tion.
- 78 12. In a wood distillation plant, the com-
79 bination with a condenser having an outlet
80 for condensed gases, said outlet having a
81 branch forming an outlet for noncondens-
82 able gases, and a suction controlled damper
83 arranged in said non-condensable gas pipe
84 for controlling the passage of gas there-
85 through.
- 86 13. In a wood distillation plant, the com-
87 bination with a condenser having an outlet,
88 of a pipe section connected thereto, a casing
89 carried by said pipe section, a cylinder car-
90 ried by said casing, a damper rod mounted
91 within said casing and pipe section, a
92 damper secured on said damper rod within
93 said pipe section, said damper rod having a
94 crank portion within said casing, a piston
95 mounted within said cylinder, a connection
96 between said piston and crank portion, and
97 a coil spring disposed under said piston
98 within said cylinder.
- 99 14. In a destructive wood distillation
100 plant, the combination with a condenser hav-
101 ing a noncondensable gas outlet, of a pipe
102 section arranged over said outlet, a damper
103 mounted within said pipe section, a casing
104 carried by said pipe section, a cylinder car-
105 ried by said casing, and a spring returned
106 piston arranged within said cylinder and
107 having a connection with said damper for
108 controlling the position of said damper
109 within said pipe section.
- 110 15. In a destructive wood distillation
111 plant, the combination with a condenser hav-
112 ing a noncondensable gas outlet pipe, a pipe
113 section arranged over said pipe, a casing ex-
114 tends from said pipe section, a damper 115 rod mounted within said casing and pipe
116 section having a crank portion within said
117 casing, a damper arranged on said damper
118 rod within said pipe section, a cylinder car-
119 ried by said casing having an annular in-
120 turned flange adjacent one end, a piston
121 mounted within said cylinder, a piston rod
122 adjustably mounted within said piston, a
123 pitman connecting said piston rod to the
124 double crank portion of said damper rod,
125 and a coil spring arranged within said cylin-
126 der under said piston having one end seated
127 upon said flange.
- 128 16. A wood distillation plant, comprising
129 a condenser, a boiler, and a connection from
130 said boiler to said condenser, means for cre-
131 ating suction within said condenser, and ad-
132 justable fluid actuated means for control-
133 ling the suction in said condenser.
- 134 17. In a wood distillation plant, the com-
135

bination with a condenser, of a wood gas line pipe having a connection with said condenser, means for creating suction within said wood gas line pipe, a damper for regulating the suction within said condenser, and a fluid actuated piston having an adjustable connection with said damper.

In testimony whereof we hereunto affix

our signatures in the presence of two witnesses.
